(57) **CLAIM**

The design for an eyeglass caddy, as shown in the accompanying drawings.

DESCRIPTION

FIG. 1 is a front elevational view of an eyeglass caddy;

FIG. 2 is a left side elevational view thereof;

FIG. 3 is a right side elevational view thereof;

FIG. 4 is a rear elevational view thereof;

FIG. 5 is a top plan view thereof; and,

FIG. 6 is a bottom plan view thereof.

The broken line showing of a pair of glasses is included for the
purpose of illustrating environment and forms no part of the
claimed design.
